DESIGN FOR A TABLE

Rankin H. Roberts, Chicago, Ill., assignor to Hibbard, Spencer, Bartlett & Co., Chicago, Ill., a corporation of Illinois

Application December 1, 1933, Serial No. 49,918

Term of patent 3½ years

To all whom it may concern:

Be it known that I, RANKIN H. ROBERTS, a citizen of the United States, residing at Chicago, in the county of Cook and State of Illinois, have invented a new, original, and ornamental Design for Tables, of which the following is a specification, reference being had to the accompanying drawing, forming a part thereof.

In the drawing:—

The single figure is a perspective view of the table showing my new design.

I claim:

The ornamental design for a table as shown.

RANKIN H. ROBERTS.
